UNITED STATES PATENT OFFICE.

CHARLES E. WEHRENBERG, OF MOUND CITY, ILLINOIS.

HAY-PRESS.

SPECIFICATION forming part of Letters Patent No. 762,367, dated June 14, 1904.

Application filed August 29, 1903. Serial No. 171,200. (No model.)

To all whom it may concern:

Be it known that I, CHARLES E. WEHRENBERG, a citizen of the United States, residing at Mound City, in the county of Pulaski and State 5 of Illinois, have invented a new and useful Hay-Press, of which the following is a specification.

My invention is an improvement in hay-presses; and the object is a press in which the leverage given the plunger-actuating mechanism is so arranged that as the hay becomes compact an increased pressure will be applied to it by the plunger.

My invention consists in the novel features of construction and combination of parts hereinafter described, particularly pointed out in the claims, and shown in the accompanying drawings, in which—

Figure 1 is a perspective view of my press. Fig. 2 is a partial longitudinal section, the 20 plunger-actuating mechanism being shown in elevation. Fig. 3 is a view in elevation of the automatic belt-shifter. Fig. 4 is a side elevation showing arrangement of the parts when the device is hand-operated.

In the drawings, A represents a truck-frame having a baling-chamber A' mounted on one end, and over the forward portion of this baling-chamber is a feed-hopper A². At the opposite end of the truck is an engine A³ of any 25 desired type. A plunger A⁴ works in the baling-chamber. To support the plunger-actuating mechanism, parallel beams B are arranged on the truck.

Journaled at the end of the truck in advance 30 of the engine is a cranked shaft B', driven by the engine pitman-rod in the usual manner and having the usual balance-wheels and a drive-pulley B².

Journaled in suitable brackets arranged on 35 the beams B are three parallel shafts C, C', and C². The shaft C carries intermediate the beams a drum C³, rigid with the shaft, and at one end a gear-wheel C⁴. The shaft C' carries at one end a gear-wheel C⁵, meshing with 40 the gear-wheel C⁴. Between the beams and adjacent the gear-wheel C⁵, which is fixed to the shaft C', is a drum C⁶, which is loose on the shaft. This drum is flanged, and at the inner end a portion C⁷ extends inward beyond

the flange. Adjacent the drum is a loose pulley C⁸, and between the loose pulley and the adjacent beam is a pulley C⁹, rotating with the shaft. The shaft C² carries at one end a pulley B³, and a belt B⁴ runs from this latter pulley to the pulley B². A drum-pulley C¹⁰ 50 is fixed on the shaft C² opposite the drum portion C⁷ and pulleys C⁸ and C⁹. A belt C¹¹ runs from the drum-pulley C¹⁰ to the drum and pulleys on the shaft C', being shifted automatically by means hereinafter described. On 55 a fixed shaft D to the rear of the other shafts is loosely mounted a flanged roller D'. To drive the plunger, a pitman D² is pivoted at one end to the plunger and at the opposite end to a link D³, which is in turn pivoted at its 60 opposite end to a short standard E. At the pivotal point D⁴ of the pitman and link is pivoted the lower end of a lever D⁵, extending upwardly and forwardly and carrying at its 65 upper end a roller D⁶. This lever has intermediate its ends a slotted link portion D⁷, slightly curved, the said slotted portion traveling on the flanged guide-roller D'. The portions of the lever at the opposite ends of this link portion are straight and arranged at a 70 slight angle to each other.

A standard F is arranged adjacent the hopper and has a roller F', similar to the roller D', mounted at its upper end. A feeder, comprising a pronged head F² and a curved stem F³, has a slotted link portion F⁴, traveling on the roller F', and a straight forwardly-extending portion F⁵, which latter is pivoted at its forward end to one end of a link F⁶, which at its other end is pivoted to the lever D⁵ intermediate the roller D⁶ and the link D⁷. 75

To the drum C³ is attached one end of a cable G, which passes over the flanged roller or pulley D⁶ and is then passed over an idle pulley G', carried by a bracket arranged on 80 the standard F, and is fastened to the lever D⁵ adjacent the pivotal point D⁴.

A cable H is secured at one end to the drum C⁶ and is carried over a pulley H', arranged in a bracket carried by the standard F, and the opposite end of the cable H is fastened to the lever D⁵ adjacent the roller D⁶. To shift the belt C¹¹, a standard J is secured to the 85

beam B adjacent the belt, and this bracket has perforated guide-lugs J', arranged in vertical alinement, in which slides vertically a rod J², and this rod carries upper and lower horizontal arms J³ and J⁴. A rod K is transversely and slidably arranged on the beams B and has depending arms K', which extend downward on each side of the belt C''. A rod K² is pivoted loosely at one end to the rod J² and at the other end to the rod K, and vertical movement of the rod J² will, by the rod K², transmit a horizontal movement to the rod K, thus sliding the belt.

When it is desired to operate the device by hand-power, the engine, belts, &c., are omitted, and a suitable crank-handle is arranged on the shaft C, and a weight L is attached to the lower end of the lever D⁵ and serves to retract the plunger. This construction is shown in Fig. 4.

The operation of my device is as follows: The belt C'' being on the tight pulley C⁹, the shaft C' will be driven, and the gear C⁵, meshing with the gear C⁴, will rotate the drum C³, winding up the cable G. This cable will draw up the lower end of the lever D⁵ until the parts assume the position shown in dotted lines in Fig. 2. At first the hay will be loose and but little pressure will be required, but as the plunger advances into the chamber the hay will become more compact; but as the pitman D² and link D⁴ are gradually brought into alinement the pressure will increase, due in part to this change of position, but due still more to the fact that the link D⁷ has been traveling over the roller D', which is the fulcrum-point of the lever, and as the plunger moves inward the distance between the pivotal point D⁴ and the fulcrum-point D' is constantly decreasing, while the distance between the point D' and the outer upper end of the lever is increasing. It will be obvious from the drawings and the previous description that the feeder will be withdrawn from the hopper and the cable H unwound from its drum by the movement of the lever D⁵, just described. As the upper or outer end of the lever D⁵ nears the limit of its path in this direction it will strike the arm J⁴ and shift the belt to the drum portion C⁷, and the drum will immediately commence to rewind the cable H on the drum portion C⁶. This will commence a reverse movement of the parts, the plunger being withdrawn and the feeder forced downward into the hopper. This movement will continue until the lever D⁵ strikes the horizontal arm J³, the parts being shown at this point of the operation in Fig. 1, and the belt is again shifted back to the pulley C⁹. By shifting the belt to the pulley C⁹ the baling operation can be discontinued without stopping the engine.

Having thus fully described my invention,

what I claim as new, and desire to secure by Letters Patent, is—

65

1. In a hay-press comprising a hopper, baling-chamber, and plunger, a pivoted pitman, a lever pivoted at one end to the pitman, means for swinging said lever, and means for changing the fulcrum-point of the lever as the plunger advances into and withdraws from the chamber.

70

2. In a hay-press comprising a hopper, baling-chamber and plunger, a pivoted pitman adapted to actuate the plunger, a lever pivoted at its lower end to the pitman and fulcrumed above it, means for swinging said lever, and means for decreasing the distance between the pivotal point of the lever and pitman and the fulcrum-point of the lever as the plunger advances into the baling-chamber.

75

3. The combination with a baling-chamber and a plunger therein, of a pitman pivoted at one end to the plunger and at the opposite end to a pivoted link, a lever having an automatically-adjustable fulcrum-point, rotatable drums, cables attached to the drums and the lever, one of said cables being adapted to move the lever in one direction and the other to move it in the opposite direction, and means for rotating the drums.

80

4. The combination with a baling-chamber and plunger, of a pivoted pitman, a lever having a changeable fulcrum-point, said lever being pivoted to the pitman, a plurality of drums, a cable attached at one end to one of said drums, and at the opposite end to the lever adjacent its pivoted end, a cable attached at one end to the other drum and at the other end to the lever adjacent its free end, a belt adapted to drive said drums, and means actuated by movement of the lever adapted to shift said belt.

85

5. The combination with a hopper, baling-chamber and plunger, of a pivoted pitman, a lever having a movable pivotal point intermediate its ends and pivoted at its lower ends to the pitman, a roller at the free end of the lever, rotatable drums, a standard having a roller at its upper end, idle pulleys carried by the standard, cables attached to the drums, one of said cables passing over the roller at the end of the lever and over one of the idle pulleys and attached to the lever adjacent its pivoted end, the second cable passing over an idle pulley and being attached to the lever adjacent the roller, a feeder extending into the hopper and having a slotted link portion working on the roller carried by the standard, a pivotal link connecting the lever and feeder, and means for alternately winding and unwinding the cables on the drums.
